HAIR CURLER

Gifford L. Hitz, Van Nuys, and Arthur A. Leisy,
Los Angeles, Calif.

Application April 29, 1939, Serial No. 270,826

8 Claims. (Cl. 132—41)

This invention relates to an improved hair curler and has, for one of its principal objects, the provision of a means for curling human hair on the subject's head, which shall be simple to operate, readily applied and which, when applied, permits the hair strand to be curled up into much closer relationship with the scalp than has heretofore been possible.

One of the important objects of this invention is to provide a hair curler or the like which may be fastened at any desired point along the length of the strand of hair whereby the curl can accordingly be made of an exact length desired.

Another object of the invention is the provision of locking means in a hair curler whereby the curler can be more conveniently used behind the head and the securing means more readily manipulated by the fingers even though the same is out of the line of direct vision.

Another and still further important object of the invention is to provide, in a hair curler construction, means wherein greater access of air to the hair being curled is allowed, and, accordingly, a better evaporation of hair curling fluids and the like.

Another and still further object of the invention resides in the provision of an improved hair curler and associated securing member whereby the entire device can be locked in position around the curled strand of hair regardless of the fact that the bulk of the hair strand increases through winding, and wherein the construction is such that the hair curler or the clamp will not show while in use.

Other and further important objects of the invention will be apparent from the disclosures in the accompanying drawing and following specification.

The invention, in a preferred form, is illustrated in the drawing and hereinafter more fully described.

In the drawing:

Figure 1 is a side elevation of the improved hair curler of this invention, showing the same in open position.

Figure 2 is a view from the swivel end of the curler looking at the same from the top of Figure 1.

Figure 3 is a view of the locking end of the curler, looking at the same from the bottom of Figure 1.

Figure 4 is an enlarged detail view, showing the swivel arrangement between bowed locking means and the curler casing and showing the device in locked position.

Figure 5 is a view similar to Figure 4, illustrating the apparatus in loose unlocked position.

As shown in the drawing:

The reference numeral 10 indicates generally the casing of the improved hair curler of this invention, the same comprising generally a tubular structure having one solid end 12, this end being provided with a central end opening 14 therein, and the wall between this solid end and the middle portion of the tube is slotted as best shown at 16, a similar series of slots 18 being formed in the wall tube at the end opposite to the end 12, most of these slots extending clear to the end of the tube as shown at 20, but certain solid portions being retained as illustrated at 22 in Figures 1 and 3.

Mounted for swivel action in the end 12 of the tube is a locking bow member 24 which has a rounded hooked end 26 as best shown in Figures 4 and 5, and this end rides inside the opening 14 of the end 12 of the tube, allowing a very free swivel action while, at the same time, securely maintaining the device in locked position whenever desired.

Mounted on the other end of the bow locking member 24 is a latch or locking element 30 in the form of a ring as best shown in Figure 3, this ring having locking projections 32 and 34. The projections 32 have a sloping forward face acting in the nature of a cam and which ride over the ends of the teeth forming a corresponding end of the tube 10. The projection 34 is made on an arc adapted to fit inside the circle of teeth, and the connected members 22, this also having a sloping face for a snap cam action in the locking movement.

The fact that the projections 32 fit outside the circle of teeth and the projection 34 fits inside and forms a positive locking structure, and the length of the bow element 24 is such with relation to the length of the tube 10 that a desired snap action is obtained.

In operation, a strand of hair is caught through the open-ended slots 18, and the fact that the free end of the strand is narrow permits it to occupy the middle of the tube. Winding proceeds until the desired length of curl is reached whereupon the bowed engaging member 24 is closed over the wound strand and snapped into a locking position over the end 20 of the tube 10. When the hair is dry, the bow 24 is compressed with the fingers, and the locking member 30 releases, permitting the tube to be withdrawn from the curl. The engaging member is locked in such a position that the

bow is between the tube and the wearer's scalp, and as the hair covers the entire length of the tube and the bow is on the inside, the curler is not visible upon ordinary observation.

The special shaping of the ball end 26 of the bow permits springing the same into the cage 12 where it remains secure.

It will be evident that herein is provided a hair curler which can be made of various different

10 materials such as metal, plastics or the like, the only requirement being that the material be non-brittle and have at least some resiliency. The same is easily applied and forms a desired curl construction with a minimum expenditure of time and labor. Furthermore, the advantage of invisibility under normal conditions of use is at once readily apparent.

We are aware that many changes may be made and numerous details of construction varied 20 throughout a wide range without departing from the spirit of the invention, and we, therefore, do not purpose limiting the patent granted hereon otherwise than as necessitated by the prior art.

We claim as our invention:

25 1. A hair curler, comprising a longitudinally slotted tube, certain of the slots forming free teeth at one end of the tube, and a bowed locking member swivelly mounted in the other end of the tube, certain of the teeth at the open end of 30 the tube being joined together for resilient latching cooperation with the locking member.

2. A hair curler, comprising a longitudinally slotted tube, certain of the slots forming free teeth at one end of the tube, and a bowed locking 35 member swivelly mounted in the other end of the tube, certain of the teeth at the open end of the tube being joined together for better cooperation with the locking member, the locking member including a ring adapted to fit over the 40 open end of the tube.

3. A hair curler, comprising a longitudinally slotted tube, certain of the slots forming free teeth at one end of the tube, and a bowed locking member swivelly mounted in the other end of 45 the tube, certain of the teeth at the open end of the tube being joined together for better cooperation with the locking member, the locking member including a ring adapted to fit over the 50 open end of the tube, said ring positioned on one end of the swivelly mounted bowed locking member.

4. A hair curler, comprising a longitudinally slotted tube, certain of the slots forming free teeth at one end of the tube, and a bowed locking 55 member swivelly mounted in the other end of

the tube, certain of the teeth at the open end of the tube being joined together for better cooperation with the locking member, the locking member including a ring adapted to fit over the open end of the tube, said ring positioned on one end of the swivelly mounted bowed locking member and cammed latching elements on the ring.

5. A hair curler, comprising a longitudinally slotted tube, certain of the slots forming free teeth at one end of the tube, and a bowed locking 10 member swivelly mounted in the other end of the tube, certain of the teeth at the open end of the tube being joined together for better cooperation with the locking member, the locking member including a ring adapted to fit over the 15 open end of the tube, said ring positioned on one end of the swivelly mounted bowed locking member and cammed latching elements on the ring, one of said cammed latching elements adapted to encircle the ring of teeth.

6. A hair curler, comprising a longitudinally slotted tube, certain of the slots forming free teeth at one end of the tube, and a bowed locking member swivelly mounted in the other end of the tube, certain of the teeth at the open end 25 of the tube being joined together for better cooperation with the locking member, the locking member including a ring adapted to fit over the open end of the tube, said ring positioned on one end of the swivelly mounted bowed locking member and cammed latching elements on the ring, one of said cammed latching elements adapted to encircle the ring of teeth, and the other of said cammed latching elements adapted to be inclosed by the ring of teeth when the 30 device is in locked position.

7. A hair curling device, comprising a tube, slots extending longitudinally of the tube, certain of the slots forming free ended teeth, the other end of the tube being provided with a restricted 40 opening therein, and a resilient bowed locking element mounted for swivel action in said opening, and a ball shaped swivel element on the end of the locking bow.

8. A hair curling device, comprising a tube, 45 slots extending longitudinally of the tube, certain of the slots forming free ended teeth, the other end of the tube being provided with a restricted opening therein, and a resilient bowed locking element mounted for swivel action in said opening, and a ball shaped swivel element on the end of the locking bow, together with a fastening ring on the other end of the bow.
